UNITED STATES PATENT OFFICE.

SAMUEL P. BOPST, OF WASHINGTON, DISTRICT OF COLUMBIA.

LUMBER-RULE.

1,308,654.

Specification of Letters Patent.

Patented July 1, 1919.

Application filed August 23, 1918. Serial No. 251,172.

To all whom it may concern:

Be it known that I, SAMUEL P. BOPST, a citizen of the United States, residing at Washington, in the District of Columbia, 5 have invented new and useful Improvements in Lumber-Rules, of which the following is a specification.

This invention relates to lumber rules, the object of the invention being to provide a 10 strong, flexible and reliable lumber measuring and handling rule, embodying in conjunction with a flexible rule or strip proper, a head and ferrule of novel construction and relation to each other, whereby the head is 15 securely fastened to the body of the rule, and adapted by reason of its particular construction to greatly facilitate the longitudinal movement of planks and the turning or twisting of the same, so as to invert the 20 boards or planks or turn the same with the reverse side up for inspection purposes.

With the above and other objects in view, the invention consists in the construction, combination and arrangement of parts as 25 herein described, illustrated and claimed.

In the accompanying drawings:

Figure 1 is a side elevation of the improved lumber rule, showing one manner of using the rule in connection with a pile of 30 lumber indicated in dotted lines.

Fig. 2 is an enlarged perspective view of a portion of the rule, showing the improved head and retaining means therefor.

Fig. 3 is an edge view of the same.

Referring to the drawings, 1 designates 35 the body of the rule which is preferably made of strong, fine grained wood, such as white hickory, the same being provided at one end with an enlarged or expanded handle 2. The rule is graduated throughout its 40 length in any standard measurement, such as feet, inches, and fractions thereof.

Secured in fixed relation to the end of the body of the rule opposite the handle 2, is 45 a multiple pronged head 3.

The head 3 comprises a substantially rectangular body 4 having a rectangular central opening 5 which is flared outwardly as indicated by dotted lines at 6 in Fig. 3. Projecting from each of the corners of the body 4 of the head 3 is a prong or spike 7, four

of such spikes being shown, two projecting in one direction and two projecting in the opposite direction.

As the connecting means between the head 55 3 and the rule 1, I employ a tang or connector 8 embodying two backwardly extending plate-like portions 9 between which the adjacent end of the body 1 of the rule is tightly held by means of fasteners 10 such 60 as rivets or the like, which provide a firm connection between the rule and the connector 8. The connector also comprises a crown or connecting portion 11 forming a shoulder which bears against the adjacent 65 face of the head 3. Extending from the shoulder 8 is a shank 12 which is primarily rectangular in cross section, but which, after being inserted through the rectangular opening 5 in the head 3, is swaged as shown in 70 Fig. 3, so as to completely and tightly fill the opening 5. This forms a strong and reliable connection between the head 3 and the connector 8, while the latter forms a secure connection between the head and the body 75 of the rule.

By reason of the construction above described, the rule, as a whole, is rendered stronger and more reliable in operation than articles of a similar kind heretofore devised, 80 and by reason of using pairs of prongs extending in opposite directions from the head a firm hold may be obtained on a board or piece of lumber not only for the purpose of dragging or pushing the lumber lengthwise, 85 but for turning the lumber over so as to present the reverse side thereof upwardly, it being understood that the prongs or spikes 7 are driven into the upper face of the clamp or board before the turning operation is attempted. The flexibility of the body 1 of the rule provides for the necessary twisting or torsional action thereon and prevents the breaking of or serious injury to the body 1 during the plank turning operation. 90 95

I claim:—

In a device of the class specified, the combination of a rule body, a head at one extremity thereof having a rectangular and outwardly flared central opening, and also 100 formed with two pairs of prongs projecting in opposite directions, the prongs of each

pair being arranged in spaced relation to each other laterally of the body of the rule, and a connector for securing said head to said rule body, said connector embodying rule body embracing and confining plate-like portions fastened to the body of the rule on opposite sides thereof, a crown por-

tion connecting said plate-like portions and forming an integral part thereof, and a shank projecting from said crown through the central opening of the head and swaged to tightly fit said flared central opening.

In testimony whereof I affix my signature.

SAMUEL P. BOPST.
